Michael D. Schaler, Inventor

UNITED STATES PATENT OFFICE.

MICHAEL D. SCHALER, OF LOWELL, NEW YORK.

SEAT-FASTENER.

SPECIFICATION forming part of Letters Patent No. 395,180, dated December 25, 1888.

Application filed May 10, 1888. Serial No. 273,403. (No model.)

To all whom it may concern:

Be it known that I, MICHAEL D. SCHALER, a citizen of the United States, residing at Lowell, in the county of Oneida and State of New York, have invented a new and useful Improvement in Seat-Fasteners, of which the following is a specification.

The invention relates to improvements in seat-fasteners, being especially adapted for the seats of wagons; and it consists in the construction and novel combination of parts hereinafter described, illustrated in the accompanying drawings, and pointed out in the claim hereto appended.

15 Figure 1 of the drawings represents a perspective view of a wagon-seat having a fastener embodying the invention attached, the same being locked. Fig. 2 represents a similar view with the fastener unlocked.

20 Referring to the drawings by letter, A designates a seat-rail, upon which rests the rider B, the lower edge of which is supported upon the upper edge of the rail and bears on the outside against the vertical flange a, rising from said rail. The seat C is secured to the top of the rider by any ordinary means.

25 D is a rectangular plate bolted or otherwise securely attached to the rear surface of the riser, and provided adjacent to its lower edge with the outstanding perforated cam-lugs E, having the upper inclined cam surface or end, e.

30 F is a rod passing through the perforation of said lug, having its upper end screw-threaded and its lower end, f, bent at right angles, in order to pass under and rest against the lower edge of the seat-rail. The said rod has on its threaded end the nut f' and washer f² and passes through the perforated cam-

35 boss G of the lever-arm g, which boss has the lower cam end, g', inclined at an equal angle to that of the cam end e. The arm g has at its free end a short outward projection for ease in turning the arm on the rod F. When 40 the inclined cam ends rest flat upon each other, their inclines being in the same direc-

tion and the whole of their meeting surfaces touching, the rectangularly-bent ends f of the rod F may be turned under the seat-rail without binding thereon. When the arm is, however, turned in the opposite direction, the inclination of the cam end g' is reversed, and it rises on the cam end e, causing the end of the rod to bind on the seat-rail and hold the riser thereto.

45 H is a button pivoted at a proper point upon the plate D in position to be turned on the lever-arm when the riser is locked upon the seat-rail. The inner edge, h, of the engaging-point of the button is rounded, so that it will hold the lever-arm more tightly to the plate 50 B the more it is turned inward on said arm.

h' is a pin standing outward from said plate in position to prevent the button from being turned up too far off the arm g.

55 It is evident that by the described means the riser and attached seat may quickly and easily be secured to the seat-rail at any desired point thereon. If the end f does not hold tightly enough on the lower edge of the seat-rail, the nut f' should be turned up till 60 said end binds.

Having described my invention, I claim—

65 In a seat-fastener, the plate D, provided with a lug, E, having an upper cam-surface, the boss G, provided with a lower cam-surface 70 resting on the lug E, and having an arm, g, and the rod F, passing through the central registering openings in the lug and boss, provided at its lower end with a bend, f, and engaged at its upper end by a nut, in combination with the button H, provided with a rounded lower end adapted to bear on the arm g, substantially as and for the purpose specified.

80 In testimony that I claim the foregoing as my own I have hereto affixed my signature in presence of two witnesses.

MICHAEL D. SCHALER.
